METHOD AND APPARATUS FOR MAKING
WIRE FABRICJames K. Watkins, Monessen, Pa., assignor to
Pittsburgh Steel Company, Pittsburgh, Pa., a
corporation of Pennsylvania

Application March 12, 1938, Serial No. 195,555

15 Claims. (Cl. 140—10)

This invention relates to methods and apparatus for making wire fabric and more particularly is concerned with the manufacture of wire fence having pickets of unequal length which are crimped to improve the appearance and strength of the fence.

Heretofore in the manufacture of wire fence or similar wire fabric, it has been the practice to crimp the longitudinally extending strand wires which give the fence a resiliency so that changes in temperature, as from winter to summer, do not result in fence sag, and also the crimping of the wires improves the appearance of the fence. Generally in the past, wire fence has been made from such longitudinal strand wires connected together by a plurality of spaced picket or stay wires which are, in one popular form of fence, welded to the strand wires. Some attempts have been made heretofore to provide such wire fence with picket or stay wires of different length as, for example, to employ a relatively short stay wire between each pair of stay wires which extend the full width, i. e., height, of the fence. These short picket wires increase the number of wires in a given length of the fence and prevent animals, rubbish or the like, from passing through the fence near the bottom thereof. Difficulty has been experienced in making welded wire fence with pickets of alternately shorter and longer lengths, and this has been due largely to expensive methods and apparatus of construction. Moreover, while the strand wires of fence have been crimped, as described above, to improve their strength and appearance, the picket or stay wires have never been crimped after being welded in place, so far as I am aware, and particularly they have not been crimped by automatic production methods and apparatus.

It is the general object of my invention to avoid and overcome the foregoing and other difficulties of and objections to known methods and apparatus for making wire fabric, and particularly wire fences, by providing improved means and methods for rapidly and inexpensively manufacturing a picket wire fence in which the pickets may be of any desired length and in which alternate pickets may extend only over a part of the height of the fence and in which all pickets may be given an attractive and strength-improving crimp.

Another object of my invention is the provision of mechanism for feeding picket or stay wires into position in wire fence fabric and by which

alternate or selected stay wires are of different but readily adjustable lengths.

Another object of my invention is the provision of mechanism for automatically forming crimps in the stay wires of wire fence fabric.

The foregoing and other objects of my invention are achieved by the provision of a wire fabric fence-building machine of the type having means for supporting and feeding strand wires forward in parallel relation, and means for welding stay wires thereto, characterized by means for alternately feeding a relatively long full-width stay wire across the strand wires and a relatively short stay wire across only part of the strand wires but in spaced parallel relation with each other, and means for crimping the stay wires between the strand wires regardless of the stay wire lengths and after they have been welded into place.

The stay wire feeding mechanism of my invention is employed with an apparatus for making wire fence, such apparatus including means for supporting strand wires in parallel relation in a plane, and means for welding stay wires to the strand wires. The stay wire feeding mechanism is characterized by the inclusion of means for gripping and feeding a stay wire transversely of the strand wires, means for alternately giving the feeding means a long and a short movement, means for adjusting the length of the long feeding movement, and means for adjusting the length of the short feeding movement.

The mechanism for crimping the stay wires of the wire fabric comprises means for advancing the fabric, dies adapted to engage with the opposite sides of a stay wire to crimp it, means for effecting relative movement between the plane of the fabric substantially at right angles to its forward movement and the dies thereby to place a stay wire between the dies or remove it from such a position, and means to close the dies about a stay wire when the dies are properly positioned to effect a crimping of the stay wire.

My method of making wire fence which comprises welding stay wires at longitudinally spaced points to longitudinally extending substantially parallel strand wires is characterized by feeding a stay wire across the full width of the substantially parallel strand wires, cutting the stay wire off and securing it to the strand wires, and thereafter feeding at least one stay wire across only part of the strand wires, cutting it off, and securing it to the spanned strand wires. The operation is repeated to provide the alternate

length stay wires along the wire fabric to thus produce a fence having pickets of at least two different heights recurrent at fixed intervals along the fabric.

5 For a better understanding of my invention reference should be had to the accompanying drawings wherein Fig. 1 is a plan view of the complete apparatus; Fig. 2 is a side elevation of the stay wire feeding mechanism; Fig. 3 is an 10 end elevation of the stay wire feeding mechanism; Fig. 4 is a side elevation of the stay wire crimping mechanism; Fig. 5 is an end elevation of the stay wire crimping mechanism; Fig. 6 is a 15 sectional view, on an enlarged scale, of the wire-crimping dies and is taken on line VI—VI of Fig. 5; and Fig. 7 is a plan view taken on line VII—VII of Fig. 5 and showing a plan view of the crimping dies and the wire fabric produced.

Since apparatus for making welded wire fabric, 20 and particularly welded wire fence, is broadly old and well known, and my invention relates merely to associated mechanisms to be applied to such known apparatus and used in combination therewith, I have neither illustrated in detail the 25 mechanism for supporting and advancing step by step, or otherwise, the longitudinal or strand wires, nor the mechanism for resistance welding the transverse picket or stay wires thereto. Suffice it to say that such apparatus comprises 30 a frame 10 including a fabric-supporting and advancing drum 12 and a bed 14 for receiving the strand wires in spaced parallel relation from suitable supply means (not shown), and for moving the strand wires in parallel relation beneath 35 a welding mechanism 16. The frame 10 includes internal driving mechanism, generally indicated at 18, and contained within the frame 10.

It will be understood that the parallel strand wires, indicated by the letter D, are received 40 upon the bed 14 and are moved by the mechanism 18 step by step over the bed, and each time the strand wires are at rest a stay wire is fed, by mechanism indicated generally at 19 and herein-after particularly described, transversely of the 45 strand wires usually at a position adjacent the welding mechanism 16. After being fed into place, each stay wire is cut off and welded to the strand wires before the strand wires are again advanced. By continuously repeating the operation, wire fabric comprising longitudinally extending strand wires and transversely directed 50 picket or stay wires is produced. Such fabric is carried over the drum 12 down between rollers 20 on the frame and is wound on the wind-up 55 reel 22 carried on arm extensions 24 of the frame 10. The crimping mechanism for crimping the strand wires D is not shown since it forms no part of my present invention but it is usually positioned to operate on the strand wires after 60 they pass over the drum 12. The mechanism for crimping the picket or stay wires is indicated generally by the numeral 26 and is positioned between the rollers 20 and the wind-up reel 22 and will hereinafter be described in detail.

65 The mechanism for feeding the stay wires includes a frame 30 which is secured to the frame 10, as best seen in Fig. 1, so that the frame 30 extends substantially at right angles to the frame 10 and the direction of the movement of the strand wires D over the bed 14. The top of the frame 30 is in substantially horizontal alignment 70 with the bed 14. The frame 30 carries a crank-shaft 32 in suitable bearings, which shaft is driven by gear 34 which meshes with a gear 36 carried upon a shaft 38 forming a part of the mechanism

18. At each end of the crank-shaft 32 is mounted a crank, indicated by the numerals 40 and 41, which cranks extend substantially at 180° to each other, as best seen in Fig. 3, and which include adjustable screws 42 and 43, whereby the effective 5 lengths of the cranks 40 and 41 can be controlled. This is done by connecting the screws 42 and 43 in fixed relation to the hubs of the cranks and receiving the threaded ends of the screws in tapped bores of blocks radially movable in suitable 10 grooves in the crank arms and carrying connecting rod pins 46 and 47.

Positioned in vertical alignment with the shaft 32 at the sides of the frame 30 are racks 48 and 50 which are mounted for vertical sliding movement in suitable gibs, indicated at 54. Each rack carries a stud pin 56 and the pins 56 are pivotally connected to the crank pins 46 and 47 by connecting rods 58 and 58a, respectively, so that upon the rotation of the crank-shaft 32 the racks 20 48 and 50 are given reciprocating movements up and down in their gibs 54. The teeth of the rack 48 engage with a hubbed pinion 60 carried in a bearing 62 and rotatably receiving a shaft 64. In like manner the teeth of the rack 50 engage 25 with a hubbed pinion 66 rotatably received in a bearing 68 and rotatably receiving the other end of the shaft 64. The shaft 64 has secured thereto at its center a wheel 72 which carries a ratchet gear 74 on its one lateral face and a ratchet gear 30 76 on its other lateral face.

Each pinion 60 and 66 carries an arm 78 and 80, respectively, to which are secured pawls 82 and 84, respectively, which engage with the ratchet gears 74 and 76, respectively. The wheel 35 72 is formed with a shoulder which fixedly carries a stay wire feed ring 88 which may be formed with a flat wire engaging face but which is preferably formed with one or more shallow grooves, as shown, usually equal in depth to about one-half the diameter of the wire being fed. Cooperating with the feed ring 88 is a feed wheel 90 40 pivotally mounted upon a short shaft 92 carried between the bifurcated portions of a lever 94 pivotally secured, as at 96, to a bracket 98 on the 45 frame 30. The other end of the lever 94 is slotted and receives a bolt 100 which is pivotally secured at one end to a cam lock 102. The other end of the bolt 100 is received in a clevis 104 pivotally secured to the frame 30 and including a tightening compression spring 106. Gears 107 and 108 connect the feed wheel 90 and the wheel 72 50 for positive feeding movement.

The frame 30 carries stay wire straightening and guiding means, indicated generally by the 55 numerals 110 and 112, which are in alignment with the wire-feeding wheel 90 and the feed ring 88. The stay wire, indicated by the letter Y, is brought from a suitable source (not shown) over the guide shive 114 and into the wire-guiding and straightening means 110 and 112 from which it passes between the feeding rolls and through an opening 116 in the frame 130 to a point just above, as shown, or, if desired, to a point just below the plane of the strand wires D carried upon 60 the bed 14. Once in position the stay wire is cut off by suitable mechanism, indicated generally at 120 and of known character, which is operated through a link 122 and a bell-crank 124 which carries a follower 126 engaging with a cam 70 128 carried on the shaft 38. The synchronized operation of the welding mechanism 16 effects the resistance welding of the cut-off stay wire to the longitudinally extending strand wires.

Before proceeding with the description of the 75

remaining parts of my apparatus it will be well to understand the operation of the stay wire feeding mechanism as just structurally described. Briefly, as the mechanism 18 carried in the frame 5 10 brings the spaced longitudinally extending parallel strand wires D to a stop on the bed 14, the mechanism drives shaft 38 and through gears 36 and 34 continuously rotates the crank-shaft 32. Movement of the crank-shaft 32 in a clockwise direction from the position shown in Fig. 2 causes the rack 48 to move upwardly due to the connecting rod 58 and the upward movement of the rack rotates pinion 60 and swings pawl-carrying bracket 78 through an arc. The pawls 82 carried by the bracket 78 engage with the ratchet gear 74 carried on the wheel 72 and thus rotate the wheel 72 and the feed ring 88. This rotary movement of the ring 88 and the simultaneous rotation of the feeding wheel 90 pulls the stay 15 20 wire Y over the shive 114 through the straightening and guiding mechanisms 110 and 112 and feeds the stay wire out transversely over or under the longitudinally extending strand wires D.

The length of the feeding movement is dependent upon the length of the crank 40 which is determined by the adjustment of the screw 42 and the position of the pin 46 as controlled thereby. For a full feeding movement the pin 46 is out near the end of the crank so that a full-length picket or stay wire is provided. For a short picket or stay wire the screw 42 is adjusted so that the pin 46 is moved in on the crank 40 to provide a relatively short throw of the crank and a short feeding movement. Once 30 35 the stay wire has been fed out over the strand wires continued rotation of the shaft 38 brings the cam 128 into engagement with the follower 126 to rock the bell-crank 124 and operate the cut-off mechanism 120 which cuts off the stay 40 wire. The synchronized operation of the welding mechanism then secures the stay wire to the strand wires as will be understood.

After the rack 48 reaches the top of its movement and starts down, the rotation of the pinion 60 is reversed and the pawl or pawls 82 carried by the bracket 78 mounted on the pinion 60 ride in a return movement over the inclined surfaces of the teeth of the ratchet gear 74 and there is no movement to feed the stay wire Y. 45 50 However, at this time the crank 41 is raising the rack 50 and the pinion 66 is rotated to carry its bracket 78 and pawl or pawls 84 against the ratchet gear 76 to effect a rotation of the wheel 72 and another feeding movement of the stay 55 60 wire Y. Thus, by making the cranks 40 and 41 of different effective lengths which can be readily done by means of the screws 42 and 43, every alternate stay wire can be made relatively short as compared to the other stay wires which are 65 70 made to extend the full height of the fence, i. e., the full width of the fabric, produced. The timing of the feeding mechanism, just described, is so coordinated with the mechanism 18, which moves the strand wires D forward step by step, that each stay wire is fully fed at the time it is in the proper position to be welded so that when it is cut off it can be immediately welded to the stationary strand wires, and as soon as this is done, the strand wires again advance so that the next 75 stay wire feeding operation can immediately follow with its cut-off and welding. The continued repetition of this operation effects the application of the stay wires to the strand wires. The adjustment of the bolt 100 and the spring 106 effects the driving tension on the stay wire posi-

tioned between the feed ring 88 and the feeding wheel 90.

After the stay wires have been applied to the strand wires as heretofore described, the wire fabric is passed over the drum 12 and down between the rollers 20 carried by the frame and onto the wind-up reel 22. Between the rollers 20 and the wind-up reel 22 the stay wire crimping mechanism 26 is positioned on the arms 24. This mechanism includes brackets 150 mounted on the arms 24 and carrying shafts 152 and 154. The shaft 154 acts as a pivot pin for pivotally mounting a plurality of pairs of pincher arms 156, as seen in Fig. 6, the longer portions of which are resiliently urged towards each other by means of tension springs 158. The shorter portions of the pincher arms 156 are formed with faces 160, each face being adapted to carry a plurality of stay wire engaging fingers 162, usually in the form of rollers, positioned as shown in Fig. 7 and staggered with relation to each other. Thus when a stay wire is gripped between the rollers and the pincher arms 156 are brought together, a stay wire is crimped in the manner shown in Fig. 7. The length of each set of pincher arms 156 along 25 30 35 shaft 154 is somewhat less than the transverse distance between the strand wires D of the fabric, so that the pincher jaws can be moved between the strand wires and to a position surrounding a stay wire without striking the strand wires. 30

In order to move the pincher arms 156 about the shaft 154 to effect a crimping operation, the shaft 152 is provided with a plurality of double cams 166, 168, 170 and 172 which are adapted to engage with suitable cam followers 174 carried between the bifurcated ends of the pincher arms 156 and adapted to simultaneously engage with the portions of the double cams on either side of the shaft 152, as will be seen from Fig. 6. The shaft 152 is given a periodic rocking movement 40 45 50 by connecting cranks 178 to the ends of the shaft near the brackets 150 and rocking the cranks by links 180 pivotally secured to levers 182 rotatably about points 184 on the frame 10. Links 186 pivotally connect the levers 182 to cam followers 188 engaging with cams 190 driven by the mechanism 18.

An important part of the crimping mechanism is the means for effecting relative movement between the wire fabric and the crimping mechanism in a direction substantially at right angles to the plane of the fabric. Such means move each stay wire into and out of position between the crimping rollers on the pincher arms. While these means may take a plurality of forms, I have 55 60 65 70 75 found that the desired movement can be readily achieved by pivotally securing arms 200 to the frame, as at 202, which arms carry at their other end rollers 204 between which the wire fabric passes. The arms 200 adjustably carry cam plates 206 which engage, as seen in Fig. 5, with cams 208 carried by the rock-shaft 152. Thus the tilting movement of the rock-shaft 152 as effected by the cams 190 causes a movement first of the arms 200 to lower the plane of the wire fabric so as to position the stay wire to be crimped between the rollers 162 carried by the pincher arms 156. The continued rocking movement of the shaft 152 causes the cam 166 to engage with the followers 174 and rock the pincher arms 156 to force the rollers 162 carried thereby into crimping engagement with the sides of the stay wire engaged.

As shown in Fig. 6, I preferably make the several cams 166, 168, 170 and 172 of progressively 75

shorter arcuate length so that the crimping operation on the particular stay wire is progressive either from end to end or from the center portion thereof outwardly. This is done because the stay wires are not stretched, and as a result the strand wires move closer together during the crimping operation, and since the crimping operation is progressive, the power required for the operation is less than that which would be required if the entire length of the stay wire were crimped at the same time.

I may make each of the cams 166, 168, 170 and 172 to operate simultaneously to crimp the stay wire with a simultaneous stretching, but while this is part of my inventive concept, it is not preferred.

It is believed that the operation of the stay wire crimping apparatus will be evident from the foregoing description. The wire fabric with the stay wires welded thereto at longitudinally spaced points and in substantially transversely extending directions is fed forward step by step through the crimping mechanism. The means 18 for achieving this feeding movement of the fabric 25 are coordinated through the cams 190 so that as the fabric stops the movement of the cams 190 first rocks the shaft 152 to effect a lowering of the plane of the fabric to bring the next stay wire to be crimped between the crimping rollers. The continued movement of the cam 190 rocks the shaft 152 farther to bring the cams 166, 168, 170 and 172 in turn into engagement with the cam followers 174 which force the crimping rollers 162 into crimping relation with the stay 35 wire. The rocking movement of the shaft 152 in the other direction as effected by the cams 190 opens up the crimping rollers 162 and the pincher arms 154 so that in the final rocking movement of the shaft 152 the cams 208 engage with the cams 40 206 to move the fabric away from the crimping rollers 162 so that the fabric can again be fed forward one step and the operation repeated. It will be understood that the stepped forward movement of the fabric is equal to the distance 45 between the stay wires.

By this mechanism a wire fabric, and particularly a wire fence, can be made as seen in Fig. 7, which includes crimped longitudinally extending strand wires D held in spaced parallel 50 relation to each other by transversely extending picket or stay wires Y, certain recurrent stay wires at longitudinally fixed intervals extending the full width or height of the fabric and being crimped in a manner similar to the strand wires 55 so that the appearance of the fence is definitely improved. The spaces between the full width stay wires receive the short picket or stay wires which are likewise crimped and both the long and short stay wires are formed with curved ends or 60 scrolls (by suitable means not shown), which scrolls overlap each other and are secured to one another. The resulting fence is of a particularly attractive appearance and is strong and resilient, and provides added strength and meshes 65 along one portion, usually the lower portion, so that it fulfills a long-felt want in the trade and achieves the objects of the invention.

The apparatus herein described is adapted to be 70 used with any of the standard wire fabric making machines and provides relatively inexpensive but rapid and satisfactory means for making wire fence having picket or stay wires of alternate lengths which are crimped after being welded in position.

While in accordance with the patent statutes I have specifically illustrated and described my invention, it should be understood that the invention is not limited thereto or thereby, but is defined in the appended claims.

I claim:

1. A wire fabric building machine of the type having means for supporting and feeding strand wires forward in parallel relation and means for securing stay wires thereto, characterized by 10 means for crimping the stay wires in the plane of the fabric, and means for effecting relative movement between the plane of the fabric and the dies to position each stay wire between the dies for the crimping operation.

2. A wire fabric building machine of the type having means for supporting and feeding strand wires forward in parallel relation and means for welding stay wires thereto, characterized by 20 means for feeding stay wires across the strand 20 wires but in spaced parallel relation with each other, and means, operable after each stay wire is welded in place, for crimping a stay wire between a pair of strand wires a plurality of times and on smooth curves lying in the plane of the 25 fabric.

3. Stay wire feeding mechanism for use with an apparatus for making wire fabric, such apparatus including means for supporting strand wires in parallel relation in a plane, and means 30 for securing stay wires to the strand wires, said stay wire feeding mechanism being characterized by the inclusion of means for gripping and feeding a stay wire transversely of the strand wires, means for alternately giving the feeding means 35 long and short movements, means for adjusting the length of the long feeding movement, and means for adjusting the length of the short feeding movement.

4. Stay wire feeding mechanism for use with 40 an apparatus for making wire fence, such apparatus including means for supporting strand wires in parallel relation in a plane, and means for welding stay wires to the strand wires, said stay wire feeding mechanism being characterized 45 by the inclusion of rolls for gripping and feeding a stay wire transversely of the strand wires, means for alternately giving the feeding rolls a turn through a greater and a less angle, means for adjusting the roll turning angle of the long feeding movement, and means for adjusting the roll turning angle of the short feeding movement.

5. Stay wire feeding mechanism for use with an apparatus for making wire fence, such apparatus including means for supporting strand wires 55 in parallel relation in a plane, and means for welding stay wires to the strand wires, said stay wire feeding mechanism being characterized by the inclusion of rolls for gripping and feeding a stay wire transversely of the strand wires, and means for alternately giving the rolls a turn through a long and a short angle, said last-named means including a crank-shaft, cranks of adjustable length secured to the crank-shaft and extending substantially at 180 degrees to each 60 other, and ratchet wheels connected to the rolls and operated by the cranks.

6. Apparatus for crimping the stay wires of wire fabric comprising means for advancing the fabric, dies adapted to engage with the opposite 70 sides of a stay wire to crimp it, means for effecting relative movement between the plane of the fabric and the dies to place a stay wire between the dies or remove it from such a position, and means to close the dies about a stay wire when 75

the dies are properly positioned to effect a crimping of the stay wire in the plane of the fabric.

7. Apparatus for crimping the stay wires of wire fabric comprising means for advancing the fabric, dies adapted to engage with the opposite sides of a stay wire to crimp it, means synchronized with the fabric advancing means for effecting relative movement between the plane of the fabric substantially at right angles to its forward movement and the dies to place a stay wire between the dies or remove it from such a position, and means synchronized with the fabric advancing means to close the dies about a stay wire when the dies are properly positioned to effect a crimping of the stay wire.

8. Apparatus for crimping the stay wires of wire fabric comprising means for advancing the fabric step by step, dies adapted to move between the strand wires and to engage with the opposite sides of a stay wire to crimp it, means for effecting relative movement between the plane of the fabric substantially at right angles to its stepped forward movement and the dies to place a stay wire between the dies or remove it from such a position, and means to close the dies about a stay wire when the dies are properly positioned to effect a crimping of the stay wire in the plane of the fabric.

9. Apparatus for crimping the stay wires of wire fabric comprising means for advancing the fabric step by step, dies adapted to engage with the opposite sides of a stay wire to crimp it on smooth curves a plurality of times between each pair of strand wires, means for effecting relative movement between the plane of the fabric substantially at right angles to its stepped forward movement and the dies to place a stay wire between the dies or remove it from such a position, and a plurality of means to close the dies progressively about a stay wire when the dies are properly positioned to effect a crimping of the stay wire.

10. Apparatus for crimping the stay wires of wire fence fabric comprising means for advancing the fabric step by step, dies adapted to engage with the opposite sides of a stay wire to crimp it on smooth curves a plurality of times between each pair of strand wires, means for effecting relative movement between the plane of the fabric substantially at right angles to its stepped forward movement and the dies to place a stay wire between the dies or remove it from such a position, a shaft, a plurality of cams on the shaft, and means to move the shaft through an angle to close the dies about a stay wire when the dies are properly positioned to effect a crimping of the stay wire.

11. That method of making wire fabric which comprises securing transverse stay wires at longitudinally spaced points to longitudinally extending substantially parallel strand wires characterized by feeding a stay wire across the full width of the substantially parallel strand wires, cutting the stay wire off and securing it to the strand wires, advancing the fabric, feeding at

least one stay wire across only part of the strand wires, cutting the stay wire off and securing it to the spanned strand wires, and repeating the operation to provide the alternate length stay wires along the wire fabric.

12. That method of making wire fabric which comprises securing transverse stay wires at longitudinally spaced points to longitudinally extending substantially parallel strand wires characterized by feeding a stay wire across the full width of the substantially parallel strand wires, cutting the stay wire off and securing it to the strand wires, advancing the fabric, feeding at least one stay wire across only part of the strand wires, cutting the stay wire off and securing it to the spanned strand wires, repeating the operation to provide the alternate length stay wires along the wire fabric, and crimping the stay wires after they have been secured in place.

13. That method of making wire fence which comprises welding transverse stay wires at longitudinally spaced points to longitudinally extending substantially parallel strand wires characterized by feeding a stay wire across the full width of the substantially parallel strand wires, cutting the stay wire off and welding it to the strand wires, advancing the fabric longitudinally of the strand wires a desired stay wire spacing distance, feeding at least one stay wire across only part of the strand wires, cutting the stay wire off and welding it to the spanned strand wires, repeating the operation to provide the alternate length stay wires along the wire fence, and crimping each stay wire in turn after welding and during the welding of a subsequent stay wire.

14. That method of making wire fence which comprises welding transverse stay wires at longitudinally spaced points to longitudinally extending substantially parallel strand wires characterized by feeding a stay wire across the full width of the substantially parallel strand wires, cutting the stay wire off and welding it to the strand wires, advancing the fabric longitudinally of the strand wires a desired stay wire spacing distance, feeding at least one stay wire across only part of the strand wires, cutting the stay wire off and welding it to the spanned strand wires, and repeating the operation to provide the alternate length stay wires along the wire fence.

15. That method of making wire fence which comprises supporting longitudinally extending substantially parallel strand wires, feeding a stay wire across the substantially parallel strand wires, cutting the stay wire off and welding it to the strand wires, advancing the fabric longitudinally of the strand wires, feeding another stay wire across at least part of the strand wires, cutting the stay wire off and welding it to the spanned strand wires, repeating the operation to provide the wire fence, and crimping each stay wire in turn after welding and during the welding of a subsequent stay wire.

JAMES K. WATKINS. 65
